United States Patent Office.

JAMES BLEASE, OF RICHMOND, INDIANA.

Letters Patent No. 77,246, dated April 28, 1868; antedated April 25, 1868.

IMPROVEMENT IN FORE-PART IRONS.

The Schedule referred to in these Letters Patent and making part of the same.

TO ALL WHOM IT MAY CONCERN:

Be it known that I, JAMES BLEASE, of the city of Richmond, and State of Indiana, have invented a new and useful Improvement in Fore-Part Irons for finishing shoes, &c.; and I do hereby declare that the following is a full, clear, and exact description of the same, reference being had to the accompanying drawings, making part of this specification, in which—

Figure 1 is a perspective view of the tool,

Figure 2 a view of the reverse side,

Figure 3 a view with the adjustable parts removed, and

Figure 4 are the adjustable parts.

The same letters in the different figures refer to corresponding parts of the invention.

The nature of my invention consists in constructing tools for finishing the edges of the soles of shoes, &c., in such a manner that the tool may be adjusted to suit the various thicknesses of soles, by means of adjustable lips; and for obtaining various styles of finish different lips may be applied to the same tool, thus dispensing with the numerous complete tools ordinarily required for the purpose. The same tool may also be used as a shoulder-iron when the adjustable parts are removed.

To enable others skilled in the art to make and use my invention, I will proceed to describe it with reference to the drawings.

a represents the tool, having a lug, *e*, formed by the recess, *I*. *b* represents the adjustable lip, which may be shouldered or made plain to give the desired finish. The said lips are provided with suitable apertures, by which they are secured in an adjustable manner on the lug *e* by means of the screw *c* and nut *d*, (as plainly shown by the drawings.) The guard *j* serves to govern the movement of the tool.

Having thus fully described my said invention, what I claim, and desire to secure by Letters Patent, is—

Adapting the tool *a* to the different thicknesses of the soles by means of the adjustable lips, substantially as set forth.

I also claim adapting the tool *a* to the different purposes herein specified by means of the detachable lips, as shown and described.

JAMES BLEASE.
